[57] CLAIM

The ornamental design for a cannula hub body with viewing lens, as shown and described.

DESCRIPTION

FIG. 1 is a perspective view of a cannula hub body with viewing lens, showing my new design;
FIG. 2 is a top plan view thereof;
FIG. 3 is a bottom plan view thereof;
FIG. 4 is a side elevational view thereof, the opposite side elevational view being identical thereto;
FIG. 5 is a front elevational view thereof; and,
FIG. 6 is a rear elevational view thereof.

FIG. 1

FIG. 2**FIG. 3****FIG. 4**

FIG. 5

FIG. 6
